UNITED STATES PATENT OFFICE

JACOB WEINTZ, OF CLEVELAND, OHIO, ASSIGNOR TO THE STRONG, CARLISLE AND HAMMOND COMPANY, OF CLEVELAND, OHIO, A CORPORATION OF OHIO

ELECTRIC FURNACE

Application filed April 26, 1926. Serial No. 104,505.

This invention relates more particularly to electric furnaces having removable heating units, and it is among the objects of the invention to provide a self-contained heater unit which can be readily removed or replaced while the furnace is under heat. A further object is the provision of an improved supporting means for the heating-units. Other objects and advantages will appear as the description proceeds.

To the accomplishment of the foregoing and related ends, the invention, then, consists in the features hereinafter fully described and particularly pointed out in the claims, the annexed drawings and the following description setting forth in detail certain means embodying the invention, such disclosed means constituting, however, but one of various forms in which the principle of the invention may be used.

In said annexed drawings:

Fig. 1 is a vertical sectional view of a portion of a furnace embodying my invention, the section being taken on the plane indicated by the line I—I, Fig. 2; Fig. 2 is a fragmentary elevational view; Fig. 3 is a vertical section taken on a plane indicated by the line III—III, Fig. 1; and Fig. 4 is a transverse section taken on a plane indicated by the line IV—IV, Fig. 1, the port closure being removed.

In the drawing, the reference character F designates a furnace housing, which may be of any detailed construction desired, and which has ports P that normally are closed, these being of a size to allow passage of the heating unit. The closure elements for the ports comprise refractory portions 5 and insulation with suitable channels for the conductors, and may be attached to the heater unit and movable therewith or may be separable as desired. The heating element itself may be of any preferred character. For example it may be of resistance type, in rod form or preferably ribbon form 6, having ter-

minals 6', and being arranged in parallel loops, each loop resting in a notch 8 in a heat-resistant insulator bar 7. Two or more of these insulator bars are employed in each heating unit, depending on the size of the unit. For the lower heating unit, the insulator bars rest upon the floor, and cut away recesses 9 are provided in the bars to allow insertion of a handling attachment which preferably has fork-like tines 10 and a handle extension 11 by which the heater may be lifted as a unit to be removed or replaced. Extending through the insulator bars of the upper heater are reinforcing bars 12 of heat-resistant metal, adapted to rest on suspension hooks 13 depending from the roof of the furnace. These suspension hooks are preferably carried by beams or mating angle irons 14, being splined in inset boxing 15 to prevent turning, but being screw threaded for engagement of take up nuts 16 which rest upon the boxing 15. If desired, similar reinforcing bars 12 may be employed in the insulator bars of the lower unit also, but ordinarily this is not necessary.

The manner of use of the device will be readily understood from the foregoing. When a lower unit is to be inserted, the port being opened, the unit resting upon the fork-like tines 10 of the handling attachment is set into place on the floor of the furnace, and where the port closure is of separable form this is put in place with the conductors extending through the channels, the terminals being turned into line or detached. The handling attachment 11 will be withdrawn from the furnace except during use as in connection with the moving of the heater unit, although in some cases I contemplate leaving the handling element in place with the heater, particularly for the lower unit. The upper heater is similarly handled, but in this case unless the port is large enough to allow manipulation onto the suspension hooks 13, the hooks are first raised out of the way by means of the nuts 16 so as to allow insertion of the

heater unit, and after this has been brought almost to position, the take up nuts 16 are adjusted to run the suspension hooks down and the insulator bar or more usually the projections 12 thereof are brought into line and the hooks are drawn up to final position. Electrical circuit connections are attached to the terminals 6' of the heating elements, and the detail of the current control being immaterial to the present invention, further description thereof is unnecessary. When a heater unit is to be removed, the converse steps are involved, viz, the lower heater element is directly lifted or handled by the handling attachment, while in the case of the upper heater unit, the nuts 16 on the suspension hooks are manipulated so as to disengage and remove the suspension hooks to give such clearance that the insulator bars supporting the heater unit may be withdrawn by the handling element without interference from the hooks.

It will thus be seen that the present construction allows of a ready and safe handling of heater units which ordinarily would be easily deformed on account of their condition at furnace temperatures, and moreover by reason of the distributed support for the elements when placed, sagging and damage is prevented.

Other modes of applying the principle of my invention may be employed, change being made as regards the features of construction, provided the means set forth in the following claims or the equivalent of such stated means be employed.

I therefore particularly point out and distinctly claim as my invention:—

1. In a device of the character described, the combination of a furnace housing, a heating element, insulator bars supporting said heating element, and suspension hooks depending from the roof of the furnace for carrying the insulator bars and heating element.
2. In a device of the character described, the combination of a furnace housing, a resistance element, insulator bars supporting said resistance element, and suspension hooks depending from the roof of the furnace for carrying the insulator bars and resistance element, said suspension hooks being mounted to allow longitudinal adjustment without turning.
3. In a device of the character described, the combination of a resistance element, insulator bars supporting said resistance element, suspension hooks for carrying the insulator bars and resistance element, beams at the upper portion of the furnace housing, inset boxing connected with said beams and splinedly engaging said suspension hooks, and take up nuts on said suspension hooks for longitudinal adjustment.
4. In a device of the character described, the combination of a furnace housing, a re-

sistance ribbon element arranged in parallel loops, insulator bars having notches for receiving such loops, suspension hooks for carrying the insulator bars and resistance element, beams at the upper portion of the furnace housing, inset boxing connected with said beams and splinedly engaging said suspension hooks, and take up nuts on said suspension hooks for longitudinal adjustment.

Signed by me this 24th day of April, 1926. 75
JACOB WEINTZ.
